PISTON

William A. Roth, St. Paul, Minn.

Application June 4, 1943, Serial No. 489,692

1 Claim. (Cl. 123—78)

1

My invention relates to an improvement in pistons for internal combustion engines of the four-cycle type. A primary object of my invention is to remove, during the exhaust stroke, practically the entire exhaust gases that are ordinarily trapped in the clearance space of the present type of internal combustion engines.

Another object of primary importance is to provide a means for increasing the amount of fuel and air mixture drawn into the cylinders during the intake stroke, without the use of supercharger means, when this is found to be desirable.

The foregoing objects provide a piston for internal combustion engines to increase efficiency, power, and a great saving in fuel during the operation of the internal combustion engine. The increased efficiency and power obtained by using my piston in internal combustion engines tends to provide an engine of smaller weight for the same power than an internal combustion engine using the ordinary type of piston.

A further feature resides in providing an internal combustion engine with lower intake and compression temperatures, thereby permitting the use of lower octane fuel for the same compression ratio, or higher compression ratio for the same octane rating.

My piston is applicable to airplane motors, wherein I believe it will develop greater efficiency with a decrease in engine weight for the power developed by the engine using my pistons. These pistons may be used to advantage in automobile, Diesel, and other engines of the four-cycle type, where performance as defined herein is desirable.

The details and further features of my piston will be more fully hereinafter set forth.

In the drawings forming a part of my specification:

Fig. 1 illustrates a diagrammatic cross-section of an internal combustion engine, showing my piston therein.

Fig. 2 is a cross-section of an alternative form of my piston.

Fig. 3 is a section on the line 3—3 of Fig. 1.

Fig. 4 is a section on the line 4—4 of Fig. 1.

My piston A may be used in any type of four-cycle internal combustion engine, and is provided with a head portion 10 which may be formed integral with the skirt 11 as illustrated in Fig. 1.

The head 10 is formed with a depending cylindrical sleeve 12 which extends into the piston in parallel relation to the wall of the skirt 11 to provide a recess 13 between the wall of the skirt 11 and the wall of the sleeve 12.

2

In the lower end of the skirt 11 I provide a sleeve 14 which is threaded inside the lower end of the sleeve 11 and is adapted to be fixed by the pins 15 to the sleeve 11 of the piston. The inner end of the sleeve 14 is in the form of a cylindrical wall 16 which is parallel to the wall 11 of the skirt of the piston and thereby provides a recess 17 which is complementary in size and shape to the annular recess 13 inside of the head of the piston A.

The cylindrical sleeve 12 and the sleeve portion 14 have the same axis and extend in the same cylindrical plane, being spaced apart and adapted to provide a bearing for the ends of the wrist pin sleeve B.

The wrist pin 18 is mounted centrally between the ends in the sleeve B in any suitable manner and is adapted to support the upper end of the connecting rod C.

The wrist pin sleeve B is adapted to slide in the piston A so that the skirts 20 and 21 on each end of the sleeve operate in a close-fitting manner in the recesses 13 and 17, respectively. An oil film which lubricates the piston A also lubricates the sleeve B, and an air cushion is built up in the recesses 13 and 17 to cushion the operation of the piston A with the sleeve B as the piston reciprocates in the engine cylinder 22.

I provide a series of large holes 23 to admit air and lubricating oil to the piston and sleeve B in the recesses 13 and 17, respectively. I also provide a series of small holes 24 at the bottom, and a similar series of small holes 24 slightly above the bottom, of each recess 13 and 17, respectively, to permit air and oil to gradually escape from these recesses in the reciprocation of the sleeve B within the piston. The size and number of the series of holes 23 and 24 to be proportioned so as to admit the air freely into the recesses 13 and 17, and to restrict the escape of air from the recesses so that an air cushion may be formed to prevent shock between the piston A and the ends of the sleeve B while in rapid motion with respect to each other.

In operation my piston A will reciprocate in the cylinder 22 in the operation of the internal combustion engine. The movement of the piston A will be different with respect to the sleeve B and the cylinder 22 during each stroke of a four-cycle engine.

At the end of the power stroke and the beginning of the exhaust stroke the upper face 25 of the sleeve B will be in contact with the face 26 at the bottom of the recess 13, the lower part 21 of the sleeve B will be withdrawn from the recess

17, the recess 17 being filled with air or gases from the crank end side of the piston. During the exhaust stroke the piston A will stay in this position with respect to the sleeve B until a point, somewhat more than one-half the length of the motion of the sleeve B is reached, when the sleeve B will begin to slow down, the piston A being at its highest rate of speed at this point will tend to continue at this highest rate of speed, and thus proceed towards the head of the cylinder at a faster rate than the sleeve B.

Simultaneously, while this action of the piston A is taking place, the air and gases in the recess 17 are being compressed, first lightly, to permit the piston A to move freely, and then compressed more strongly as the compressed gases fail to escape through the holes 24 as fast as they are being compressed, thus checking the speed of the piston A, and bringing it to rest, at the end of its forward motion, at the same time that the sleeve B comes to the end of its forward motion, and thus contact is made between the faces 27 and 28 of the sleeves B and 14, respectively, without shock.

This action of the piston A is the result of the inertia forces residing in the piston A. As the acceleration at the beginning of the stroke is high, the inertia force of the piston A holds it in the position it had at the beginning of the stroke until the inertia becomes zero at a point a little more than one-half the length of the stroke of the sleeve B where the inertia force is reversed, building up rapidly to a value higher than it had at the beginning of the stroke. With the gases in the recess 17 building up a pressure rapidly enough to counteract the inertia force of the piston A, it is brought to the end of its forward motion and into contact with the sleeve B without shock, and when timed with the closing of the exhaust valve, which should close at the time the piston comes into near but not actual contact, and close at about the same rate as the piston A moves near the end of the stroke, thus expelling practically all of the exhaust gases above piston head 10. Somewhat better results may be had when used with sleeve-valve engines.

The second series of holes 24 somewhat above the bottom of the recess 17 and 13 are for the purpose of allowing the compressed air and gases to escape more rapidly, thus permitting the piston A to more quickly reach a point near the end of its motion, but after this series of holes is closed by the ends of the sleeves B passing them, the remaining holes 24 at the bottom of the recesses will let the compressed gases out still more slowly, thus insuring that no metal to metal shock results. Sufficient lubricating oil will enter the holes 23 and 24 during the operation of the piston to lubricate the bearing surfaces and to form a seal therebetween to prevent the escape of the compressed air and gases from the recesses except through the holes 24. Any excess of oil tending to accumulate in the recesses 13 and 17 will be forced out through the holes 24 to prevent water-hammer.

In order to more completely expell the entire exhaust gases during the exhaust stroke, it is necessary to modify the shape of the combustion chamber when my piston is in use.

As the piston A reaches the end of its motion at the end of the exhaust stroke which then becomes the beginning of the suction stroke, the piston remains in the position it then has, that is, with the bottom edge 27 of the sleeve 21 in contact with the face 28, the upper sleeve 20 being

withdrawn from the recess 13, this recess filling with air and gases from the crank side of the piston, the piston A holding this position with respect to the sleeve B up to a point somewhat less than one-half the length of the stroke of the sleeve B. During this time the inertia force acting in opposition to the motion of the sleeve B decreases rapidly from a high value at the beginning of the suction stroke to zero at a point somewhat less than one-half the stroke of the sleeve B.

From this point on, the inertia is again reversed, acting now towards the crank end of the piston, the sleeve B, through the motion of the crank and connecting rod, slowing up, while the piston tends to continue at the same speed, thus the sleeve 21 being withdrawn from the recess 17 while the sleeve 20 enters the recess 13, compressing the air and gases in the recess 13 and similarly as in the exhaust stroke, bringing the piston A to rest without shock, with the face 25 in contact with the face 26. The piston A comes to the end of its motion at the same time as the sleeve B comes to the end of its motion. That is, the piston A and the sleeve B come to rest simultaneously, the piston A moving further than the sleeve B by the length of the clearance space, which equals the length of the motion of the sleeve B in the recesses 13 and 17.

The timing of the opening of the suction valve must be such that as the piston A leaves the cylinder head, the valve follows the piston A closely without being in contact with it. This action of the piston A draws a full cylinder of a gas and air mixture with full throttle opening, this gas and air mixture not being diluted with hot exhaust gases, will have a lower temperature at the beginning of the compression stroke, thus insuring a lower temperature at the end of the compression stroke, and this lower compression temperature permitting the use of fuel of lower octane rating since the danger of preignition or detonation is absent. Also, the fuel and air mixture being free from exhaust gases will burn more quickly and completely, thus higher efficiency and greater power are assured. When less power is desired, part throttle operation will result in the same high efficiency in the absence of the blanketing effect of the exhaust gases.

At the beginning of the compression stroke, the piston A will remain in the position it has at the end of the suction stroke; that is, the face 26 will be in contact with the face 25 and will remain in this position throughout the compression stroke as well as the power stroke. During the compression stroke the inertia forces will act, or tend to act, identically the same as during the exhaust stroke, but here during the compression stroke the fuel and air mixture being compressed, the total pressure on the entire area of the head of the piston A will rise to a higher value during all parts of the stroke than the inertia forces, and thus keep the piston A in the same position with respect to the sleeve B during the entire compression stroke as it had at the beginning of the compression stroke, the force on the piston due to the compression of the fuel and air charge, acting counter to the inertia force during the last part of the piston stroke, the piston A with the sleeve B acting together as a solid piston.

During the power stroke, after the gases have been ignited, the compressed gas and air mixture will rise to a still higher pressure, thus holding the piston A in the same relation to the sleeve

B that it had at the beginning of the compression stroke, during the compression stroke, and will remain so to the end of the power stroke, the same as a solid piston.

At the end of the power stroke the cycle will be repeated as above described.

I claim:

In a gas engine having a cylinder and piston rod, a piston with outer walls engaging the inner walls of the cylinder, a cylindrical sleeve connected with the piston rod and reciprocable within the piston for operating the same and having annular end walls of substantial width, cylindrical cups connected with the piston end

walls and shaped and positioned to form annular chambers for receiving the annular ends of said sleeve, and two rings of apertures through the walls of both said cups, the apertures of the outer ring in each case being of large diameter to admit crank case gas and oil freely into said annular chamber, and the inner ring apertures in each case being very much smaller and being positioned close to the inner ends of the annular chambers to permit only slow discharge therefrom for effecting a strong cushioning action in the transmission of the force of reciprocation of the sleeve in both directions to the piston.

WILLIAM A. ROTH.
